UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 22, 1920. Serial No. 375,704.

To all whom it may concern:

Be it known that I, EDGAR H. CLARK, a citizen of the United States of America, residing at Richmond Hill, in the county of 5 Queens and State of New York, have invented certain new and useful Improvements in Telephone-Exchange Systems, of which the following is a full, clear, concise, and exact description.

10 This invention relates to telephone exchange systems employing automatic switching apparatus for establishing talking connections between subscribers' lines. More particularly, the invention relates to a system involving a plurality of offices and in which facilities are provided for the establishment of talking connections between subscribers' lines belonging to an office equipped with switches of the power driven type, that 15 is, switches arranged to be driven from a continuously operating source of kinetic energy, and subscribers' lines belonging to an office equipped with switches of the step-by-step type.

20 An object of the invention is the provision, in a system of the foregoing character, of means whereby a subscriber's line, terminating in an office provided with switches of the power-driven type, may be extended to 25 other subscribers' lines in the same office or to subscribers' lines in another office equipped with power-driven switches or to a distant office equipped with switches of the step-by-step type, together with means at 30 the originating office for controlling the selective operation of switches of either type.

35 A feature of this invention is the provision of a class register for altering the circuits of the sending equipment of the type employed for controlling power-driven switches, comprising a fundamental circuit, counting relays, and registers, in such manner that when the desired line terminates in the originating office, or in an office having 40 switching mechanism of the power-driven type, the sending equipment will function in the usual manner to control such power-driven switches, but when the desired line terminates in an office having switching mechanism of the step-by-step type, the 45 sending equipment will function in a different manner to control such switches.

50 A further feature of the invention is the provision of an interrupting device associated with the circuits of the sending equip-

ment for opening and closing the fundamental circuit to cause the stepping of step-by-step switches in accordance with the setting of the registers of the sending equipment.

55 Such other further features as are contemplated by the present invention will become apparent from the following description and the appended claims.

The drawings, when arranged with Figure 2 at the right of Figure 1, Figure 3 below Figure 1, and Figure 4 at the right of Figure 3, with the lines which are drawn to the edges of the respective sheets in alignment, show so much of a complete telephone exchange as is necessary to disclose this invention. Figure 1 represents a calling subscriber's line and an operator's position provided with a link circuit terminating in an answering plug and in an office selector 70 switch. Figure 2 represents diagrammatically two offices of the exchange to which the office selector of Figure 1 has access, one office X being represented in the upper portion of the figure as having mechanical 75 switching equipment of the power-driven panel type, and the other office Y represented in the lower portion of the figure as having switching equipment of the step-by-step type, and called subscribers' lines terminating in each of the offices. Figure 3 represents the operator's sending equipment; Figure 4 represents a portion only of the keys of the operator's keyboard and the registers upon which the operator sets up the numbers of the desired lines for controlling the setting of the selector switches.

80 In the system embodying this invention, the number of the line desired by the calling subscriber is set up on a set of registering mechanisms at the originating office, the first digit of the number determining the particular office of the exchange in which the desired line terminates. The office register which takes a setting in accordance with the 85 first or office digit of the number is provided with extra contacts which serve as a class switch to alter the sending and control circuits of the operator's sending equipment in accordance with the nature of the office to 90 which the calling line is to be connected by the office selector switch. On calls local to the office in which the call originates, or on calls into offices provided with power-driven switches which are set in accordance with re- 95

vertive impulses sent back to the operator's sender through the selective movements of the switches, the class switch contacts of the office register permit the sender circuits to 5 function in the well-known and usual manner. On calls into offices provided with selector switches of the step-by-step type, which are selectively controlled at the sender by impulses transmitted thereto by the selective 10 opening and closing of the fundamental circuit leading thereto, the class switch contacts of the office register cause the operation of a stepping relay at the sender under the control of the interrupter to selectively open 15 and close the fundamental circuit in accordance with the setting of the number registers. The sets of impulses corresponding to the several digits of the line designation are properly spaced to permit the trunk hunting 20 movements of the selector switches by means of a slow-to-energize relay which controls the advance of the sender sequence switch.

The office selector shown in Figure 1 is of the type shown and disclosed in Patent 25 No. 1,123,696 issued January 5, 1915 to Craft and Reynolds. To simplify the circuits of the office selector and of the operator's sender, the office selector is shown as provided with a single set of shaft wipers and 30 is therefore adapted to be set by a single set of directive impulses controlled by the office register. The incoming selector and final selector of the office represented in the upper portion of Figure 2 at X have, in order to 35 simplify the circuits, been diagrammatically represented by a set of shaft wipers of each switch. These switches are of the panel type shown in the patent to Craft and Reynolds above referred to and function in the well-known manner.

40 The office represented in the lower portion of Figure 2 by character Y is provided with step-by-step switches of the type disclosed in Patent No. 1,231,013 issued June 45 26, 1917 to C. L. Goodrum. A part only of the circuits of the first selector switch have been disclosed, the second selector and connector switch being represented by the wipers of such switches.

50 In Figures 1 and 3 sequence switches 100 and 300 respectively have been shown. These switches are of substantially the same type as disclosed in Patent No. 1,127,808, issued February 9, 1915 to Reynolds and 55 Baldwin. Each switch is provided with a motor magnet, which, when energized, forces a rotatably mounted disc into contact with a constantly rotating disc and thereby rotates a spindle on which are mounted a 60 number of contact operating cams. Cams 102 to 111 of sequence switch 100, and cams 302 to 313, 311' to 313' of sequence switch 300 are arranged to close circuits only in the 65 positions indicated by the numerals adjacent thereto. Cams 101 and 301 are so arranged

that circuits are completed through the motor magnets 100 and 300 respectively in all positions except those indicated by the numerals adjacent thereto.

The registers shown in Figure 4 are of the sequence switch type and control the contact closing cams shown immediately above and beneath their respective operating magnets. The registers are all started over a common circuit closed through contacts of the units keys of the operator's keyboard and each register continues in rotation until one of the cams shown above the magnet winding closes a contact which is grounded through one of the operator's digit keys, 70 when the circuit of the register magnet is opened. Each register therefore assumes a 75 position corresponding to the position of the digit key in the bank which the operator has depressed.

80 The organization and operation of the system disclosed may best be understood by a detailed description of the establishment of a connection, first from the line of subscriber A to the line of subscriber B in the office X by means of switching mechanism of the power-driven type, and secondly from the line of subscriber A to the line of subscriber C in the office Y, over switching mechanism of both the power-driven type 85 and of the step-by-step type.

Connection with an office equipped with power-driven switches.

90 It will first be assumed that subscriber A 100 desires a connection with subscriber B, whose line designation is 96975, and removes his receiver from the switchhook to 105 initiate the call. Upon the removal of the receiver from the switchhook, a circuit is closed for the line relay 18 extending from 110 grounded battery through the left-hand winding of the line relay, the outer left-hand armature and back contact of cut-off relay 10, thence over the subscriber's line 115 loop and returning through the inner left-hand armature and back contact of relay 10 and the right-hand winding of line relay 18 to ground. The energization of line relay 18 closes a circuit for the line lamp 19 120 in an obvious manner. The operator whose set is designated by O, upon observing the lighting of line lamp 19, inserts the plug P of one of her cord circuits into the jack J which is associated with the lighted line 125 lamp 19. This results in the establishment of a circuit extending from grounded battery through the winding of cut-off relay 10, over the sleeve contacts of jack J and plug P, and thence to ground through the winding 130 of relay 112. The energization of cut-off relay 10 removes the line relay 18 and its associated line lamp from the control of the subscriber's line. The energization of relay 112 completes a circuit extending from

grounded battery through the magnet winding of sequence switch 100, the upper left-hand contact of sequence switch cam 102 (1) and to ground through the front contact 5 and armature of relay 112. The sequence switch 100 is thereby driven into position 2 under the control of its contact 101.

When the sequence switch 100 moves into position 2, a circuit is established for relay 10 314 associated with the operator's sending circuits, which circuit may be traced from grounded battery through the winding of relay 314, the upper right-hand contact of sequence switch cam 302 (1) to conductor 15 113, and thence to ground through the lower contact of sequence switch cam 103 (2). Relay 314 upon energizing closes a locking circuit for itself extending through its winding, the lower contact of sequence 20 switch cam 302 (1 to 16), the right-hand armature and front contact of relay 314 and thence over conductor 114 to ground at the upper contact of sequence switch cam 103 (2 to 11). At its left-hand armature and 25 front contact, relay 314 closes a circuit for driving the sender sequence switch 300 out of position 1 and into position 2, this circuit extending from grounded battery through the magnet winding of sequence 30 switch 300, the upper right-hand contact of sequence switch cam 303 (1), and thence to ground at the front contact and left-hand armature of relay 314.

The operator, upon extending the connection to the calling subscriber's line, depresses her listening key K, thereby connecting her set O with the subscriber's line and receives instructions from the calling subscriber for the further extension of the 40 connection. In accordance with the instructions received, the operator depresses keys of her key-board corresponding to the number of the line desired. Under the assumption that the calling subscriber desires connection with line B located in an office having power-driven switches, the number of such line being 96975, the operator depresses office key K', thousands key K², hundreds key K³, tens key K⁴ and units key K⁵.

Upon the depression of units key K⁵, a circuit is established for starting the register switches, 410, 420, 430, 440 and 450, which circuit extends through the windings of the magnets of these registers in parallel 55 and thence over conductor 470 to ground at the right-hand contact of units key K⁵. Each of these registers will thereupon move from the position in which it has now been found to a position determined by the keys 60 K¹ to K⁵ respectively. In the case of register switch 410, the movement will continue until the ninth position is reached, in which a circuit is established from the grounded contact at key K¹, register switch contact 65 411 (9), the winding of relay 471, and thence

to grounded battery. Relay 471 attracts its armatures, thereby opening at its right-hand armature contacts the energizing circuit of the motor magnet of register switch 410. At the same time, a circuit is established from grounded battery through the winding of relay 477 over the common conductor 478, the front contact and left-hand armature of relay 471, common conductor 479, and thence by one path through the winding of relay 480, to ground, and by a second path through the left-hand armatures and back contacts of relays 472 and 475 to ground. It will be noted that relay 477 will energize in this circuit, but that relay 480 will be short-circuited until each of the left-hand armatures of relays 471 to 475 inclusive have been attracted.

The setting of the thousands register, the hundreds register, the tens register and the units register is similar to that described in connection with the setting of the office register and these settings take place simultaneously. When all are completed, the registers will be in the following positions: the office register in position 9; the thousands register in position 6; the hundreds register in position 9; the tens register in position 7; and the units register in position 5.

At this time the shunt around the winding of relay 480 will be removed and current flowing therethrough will cause its energization. A circuit is thereby established extending from grounded battery through the magnet winding of sequence switch 300, the upper contact of sequence switch cam 304 (2), and thence to ground through the armature and front contact of relay 480. Sequence switch 300 thereupon moves under the control of its contact 301, out of position 2 and into position 3.

When sequence switch 300 reaches position 3, a circuit is established from ground at sequence switch cam 305, extending over the common conductor 481 and thence in parallel through the windings of the release magnets 482 to 486 inclusive to grounded battery. The energization of these release magnets causes the release of the keys K¹ to K⁵ inclusive, thereby deenergizing relays 471 to 475 inclusive. Each of these relays retracts its armatures and in so doing causes the deenergization of relays 477 and 480.

Relay 477 in retracting its armature establishes a circuit extending from grounded battery through the magnet winding of sequence switch 300, the lower contact of sequence switch cam 304 (3) and thence to ground at the armature and back contact of relay 477. Sequence switch 300 under the control of its contact 301 moves into its fourth position. In this position a circuit, known as the fundamental circuit, is established which extends from grounded battery through the winding of relay 115 at 130

the office selector switch 116, the lower right-hand contact of sequence switch cam 104, conductor 117, the right-hand armature and back contact of stepping relay 315, the right-hand armature and back contact of counting relay 0', the winding of stepping relay 316, the upper left-hand contact of sequence switch cam 306 (4), conductor 118, and thence to ground through the lower left-hand contact of sequence switch cam 105 (2 and 3).

Relay 115 energizes in this circuit, closing through its left-hand armature and front contact a locking circuit for itself, extending through the lower left-hand contact of sequence switch cam 104, (2 and 3), and thence over the fundamental circuit previously traced. This circuit maintains relay 115 energized after the sequence switch is driven out of position 2, a circuit for advancing sequence switch 100 now extending from grounded battery through the magnet winding of sequence switch 100, the lower right-hand contact of sequence switch cam 106 (2), and thence to ground at the right-hand armature and front contact of relay 115.

In position 3 of sequence switch 100, a circuit is established extending from grounded battery through the winding of the up-drive magnet 119, the lower left-hand contact of sequence switch cam 107 (3), and thence to ground at the right-hand armature and front contact of relay 115. Magnet 119 attracts its armature and in so doing presses the depending portion 120 of the switch shaft against the constantly rotating roller 121, whereby the brush carriage 122 is elevated. As the brush 123 passes over the conducting segments of commutator 124, the stepping relay 316 is intermittently de-energized and energized.

Upon the initial energization of stepping relay 316, a circuit is established extending from ground at the armature of relay 316 through the upper left-hand contact of sequence switch cam 307 (4), the upper right-hand contact of the office register cam 412 (9), conductor 353, to the armature and back contact of counting relay 9', the winding of counting relay 9 to grounded battery. Relay 9 is thereupon energized and completes a locking circuit for itself extending from grounded battery through its winding, the winding of relay 9', the armature and front contact of relay 9, and thence to ground at the upper right-hand contact of sequence switch cam 308 (4). Counting relay 9', however, is shunted at this time through the conductor 353 over the circuit previously traced and does not energize until the stepping relay 316 retracts its armature.

When the brush 123 passes over the first conducting segment of commutator 124, re-

lay 316, through the shunt thus established, becomes deenergized and thereupon retracts its armature. This results in the energization of counting relay 9' which thereupon transfers the ground connected to conductor 353 to the armature and back contact of counting relay 8' to the winding of relay 8, and thence to grounded battery. Relay 8 is now energized over the circuit leading from ground at the armature contact of stepping relay 316, sequence switch cam 307 (4), as previously traced through conductor 353, the armature and front contact of relay 9', the armature and contact of counting relay 8', the winding of counting relay 8, and thence to grounded battery. In a similar manner each one of the upper counting relays 8' to 0' is energized by the passing of brush 123 over the segments of commutator 124 and the consequent deenergization of stepping relay 316. When counting relay 0' is energized by attracting its right-hand armature, it opens the fundamental circuit, thereby causing the deenergization of relay 115.

The energization of counting relay 0' also results in the establishment of a circuit extending from grounded battery through the winding of sequence switch 300, the lower right-hand contact of office register cam 413 (9), conductor 322, the front contact and left-hand armature of relay 0' and thence to ground at the upper left-hand contact of sequence switch cam 308 (4). Sequence switch 300 under the control of its contact 301 moves its cams into the sixth position, whereupon the locking circuit of the energized counting relays is broken at the upper right-hand contact of sequence switch cam 308 (4).

The deenergization of relay 115 results in the opening of the circuit through the up-drive magnet 119 for arresting the upward movement of the switch shaft, and in the establishment of a circuit for driving sequence switch 100 out of position 3 and into position 6. This circuit may be traced from grounded battery through the magnet winding of sequence switch 100, the lower left-hand contact of sequence switch cam 106 (3) and thence to ground at the back contact and right-hand armature of relay 115.

Since, as has been assumed, the office selector has only one selective movement, its wipers may now be driven over the selected group of contacts in their hunting movement to select an idle trunk from the group leading to the desired office. To accomplish this hunting movement a circuit is established for the test relay 125, which may be traced from grounded battery through the right-hand winding of this relay and thence to ground at the lower contact of sequence switch cam 108 (4 to 6). Relay 125,

- upon energizing, closes a locking circuit for itself extending from grounded battery through its left-hand winding, its inner left-hand armature and front contact and 5 thence to the test wiper 126. If the wipers are now resting upon the terminals of a busy trunk, there will be ground potential upon the test terminal of the trunk and test relay 125 will therefore remain locked after 10 its initial energizing circuit is opened at sequence switch cam 108 when sequence switch 100 leaves position 6 which it does immediately upon the energization of relay 125. The circuit for driving sequence switch 100 15 out of position 6 and into position 7 may be traced from grounded battery through the magnet winding of sequence switch 100, the lower right-hand contact of sequence switch cam 109 (6), and thence to ground 20 through the front contact and right-hand armature of relay 125. With sequence switch 100 in position 7, and relay 125 locked up, a circuit is now established for the up-drive magnet 119 for driving the 25 brush carriage upwardly in search of an idle trunk in the selected group of trunks. This circuit may be traced from grounded battery through the winding of the up-drive magnet 119, the lower right-hand contact of sequence switch cam 107 (7) and thence to ground at the right-hand armature and front contact of relay 125. As soon 30 as an idle trunk is found; the locking circuit through the left-hand winding of relay 125 is opened and this relay deenergizes as soon as the brush set has been centrally positioned upon the terminals of the selected idle trunk, when a locking circuit extending through the right-hand winding of 35 relay 125, through the upper contact of sequence switch cam 108 (7), the outer left-hand armature and front contact of relay 125, over conductor 127 to ground at commutator segment 128 and brush 129, is 40 opened.
- Relay 125 upon deenergizing opens the circuit of up-drive magnet and at its right-hand armature and back contact closes a circuit extending through the lower left-hand contact of sequence switch cam 109 (7) and through the winding of sequence switch 100 for driving the sequence switch out of position 7 and into position 11. In 45 position 11, conductors 117 and 118 of the fundamental circuit are extended through the lower contacts of sequence switch cams 110 and 111 respectively, to the talking conductors of the link circuit and thence over the wipers of the office selector to the conductors of the selected inter-office trunk. The stepping relay 316 of the office sender 50 is now energized over the fundamental circuit in series with the control relay (not shown) of the incoming selector 200 in the selected office X. In view of the fact that
- this incoming selector is of the well-known type, and functions in the well-known manner, it has been thought unnecessary to illustrate the control relay or other controlling circuits of this selector. 55
- The circuit over which the relay 316 is energized may be traced in part, over conductor 117, the right-hand armature and back-contact of relay 315, the right-hand armature and back contact of counting relay 0', the winding of stepping relay 316, the lower right-hand contact of sequence switch cam 306 (6), conductor 317, the lower right-hand contact of office register cam 414 (9), conductor 318, and thence to conductor 118. 60
- Stepping relay 316 upon energizing closes a circuit extending from ground at its armature contacts through the lower contact of sequence switch cam 309 (6), right-hand contact of the thousands register cam 421 (6), conductor 354, the armature and back contact of counting relay 3', the winding of counting relay 3, and thence to grounded battery. The method of translation for 65 changing the registration set up in accordance with the decimal system of notation upon the sender registers for controlling panel type switches which operate upon a non-decimal selective basis, being well known in the art, is not described in detail herein. For such detailed description, reference may be had to Patent No. 1,345,016, issued June 29, 1920 to A. E. Lundell and F. A. Stearn. The energization of counting 70 relay 3 causes the establishment of a locking circuit extending through the winding of relay 3, the winding of relay 3', the armature and front contact of relay 3, and thence to ground at the upper right-hand contact of sequence switch cam 308 (6 to 6 $\frac{1}{2}$). Relay 3' does not energize at this time, however, since its winding is shunted by ground connected at the armature contacts of stepping relay 316 over conductor 354. When in 75 response to the upward movement of the brush shaft of the incoming selector, the stepping relay 316 is shunted out in the well-known manner, the ground connected to conductor 354 is removed and counting 80 relay 3' energizes, transferring the ground connected to conductor 354 through its armature and front contact and thence through the armature and back contact of relay 2' and thence through the winding of relay 2 85 to battery and ground. In the well-known manner each counting relay in turn is energized until relay 0' attracts its armatures, whereupon the fundamental circuit is broken at the right-hand armature contacts of relay 0'. 90
- Relay 0' also upon energizing closes a circuit for driving sequence switch 300 out of position 6 and into position 8. This circuit may be traced from grounded battery 95

through the winding of sequence switch 300, the lower right-hand contact of office register cam 413 (9), the front contact and left-hand armature of relay 0', sequence switch cam 310 (6), and thence to ground through the left-hand contact of office register cam 415 (9).

With sequence switch 300 in position 8, the fundamental circuit is again established 10 between the incoming selector switch and the stepping relay 316 of the sender over conductor 117, the right-hand armature and back contact of relay 315, the right-hand armature and back contact of relay 0', the 15 winding of stepping relay 316, the upper left-hand contact of sequence switch cam 306 and thence over conductor 118. Incoming group selection now takes place under the control of the thousands and hundreds 20 registers. The energization of relay 316 now closes a circuit from ground at the armature of relay 316 through the upper contact of sequence switch cam 309 (8), the lower contact of office register cam 416 25 (9), the lower contact of the thousands register cam 422 (6), the upper contact of the hundreds register cam 431 (9), conductor 355, armature and back contact of relay 1', the winding of relay 1, and thence 30 to grounded battery. Relay 1 energizes in this circuit and closes a locking circuit for itself extending through its winding 35 through the winding of relay 1', the armature and front contact of relay 1, and thence to ground at the upper right-hand contact 40 of sequence switch cam 308 (8 to 8 $\frac{1}{2}$). Relay 1' does not energize at this time since its winding is shunted at the armature contacts of stepping relay 316. When, however, 45 in the group selection movement of the incoming selector shaft, an intermittent ground is connected to the fundamental circuit and the relay 316 becomes deenergized, the shunt is removed from around the winding of relay 1' and this relay energizes, transferring at its armature contacts the ground on conductor 355 to the winding of 50 relay 0. Upon the next deenergization of stepping relay 316, relay 0' energizes, opening the fundamental circuit at its right-hand armature contacts and closing at its left-hand armature and front contact, a circuit for driving sequence switch 300 out of position 55 8 and into position 10, this circuit extending as previously traced through sequence switch cam 308 (8) and through office register cam 413 (9).

After the group selection movement of the incoming selector switch 200, this selector switch hunts for an idle trunk in the selected group extending to a final selector switch 201. When such an idle trunk has been found, the fundamental circuit previously traced through the winding of relay 60 316 is extended through the winding of the

control relay (not shown) of the final selector switch 201. Final hundreds selection may now take place.

Upon the initial energization of stepping relay 316 over the fundamental circuit, a 70 circuit is established from ground at the armature contacts of relay 316 through the upper right-hand contact of sequence switch cam 307 (10), the upper right-hand contact of the hundreds register cam 433 (9) over conductor 353, the armature contacts of counting relay 9', and thence through winding of counting relay 9 to grounded battery. In the well-known manner counting relay 9 locks up through the winding of 75 counting relay 9', the counting relay 9', however, remaining deenergized until the shunt around its winding is removed by the deenergization of stepping relay 316, which takes place upon the upward movement of 80 the final selector switch in its brush selecting movement. In the well-known manner counting relays 8' to 0' energize and when counting relay 0' energizes, the fundamental circuit is opened at the right-hand armature contacts of this relay, and a circuit is closed at the left-hand armature contacts for driving sequence switch 300 out of position 85 10 and into position 12. Upon leaving position 10, the counting relays are unlocked and the circuits of the sender prepared for tens selections. 90

With sequence switch 300 in position 12, the fundamental circuit is again established and relay 316 again energizes, closing a circuit extending from ground at its armature contacts through the lower right-hand contact of sequence switch cam 307 (12), the lower left-hand contact 441 (8) 100 of the tens register, conductor 357, the armature and back contact of relay 7', and thence through the winding of relay 7 to grounded battery. Relay 7 in the well-known manner closes a locking circuit for itself extending through the winding of 105 relay 7', relay 7', however, remaining deenergized until stepping relay 316 deenergizes, when the final selector shaft 201 encounters the first conducting segment of its 110 commutator during the tens selection movement of its wiper shaft. When relay 7' becomes energized, transferring the ground connection on conductor 357 to the winding of relay 6, counting relays 6' to 0' energize 115 in the well-known manner, and when relay 0' energizes, the fundamental circuit is again opened at the right-hand armature contacts of this relay and a circuit is closed at the left-hand contacts of this relay for driving sequence switch 300 out of position 120 12 and into position 14. Upon leaving position 12, the locked-up counting relays become deenergized to prepare the circuits of the sender for units selection. 125

With sequence switch 300 in position 14, 130

the fundamental circuit extending through the winding of relay 316 is again established and relay 316 energizes, closing a circuit extending from ground at its armature contacts through the lower left-hand contact of sequence switch cam 307 (14), the upper right-hand contact of units register cam 451, over conductor 358, the armature and back contact of counting relay 5', and thence 10 through the winding of relay 5 to grounded battery. Relay 5 energizes in this circuit, closing a locking circuit for itself extending through the winding of relay 5' to ground at the upper right-hand contact of sequence 15 switch cam 308 (14 to 14₁). Relay 5', however, does not energize in this circuit since its winding is shunted by ground on conductor 358. As soon as relay 316 becomes de-energized due to the intermittent grounding 20 of the fundamental circuit during the units selection movement of the final selector switch, the shunt around relay 5' is removed and this relay energizes transferring the ground connection on conductor 358 to the 25 winding of counting relay 4. In the well-known manner counting relays 4' to 0' energize in succession, and when relay 0' energizes, the fundamental circuit is opened at its right-hand armature contacts, and a circuit 30 is closed through its left-hand armature contacts for driving sequence switch 300 out of position 14 and into position 16.

Upon leaving position 14, the locked-up counting relays are deenergized. Upon 35 reaching position 16 a circuit is closed extending from ground at sequence switch cam 311 through the lower left-hand contact of sequence switch cam 102 (11), and through the magnet winding of sequence switch 100, 40 to grounded battery for driving sequence switch 100 out of position 11 and into the talking position, 16. Upon leaving position 11, the conductors 117 and 118 of the fundamental circuit are disconnected from the 45 talking strands of the link circuit and the shaft wipers 134 and 135 are connected over the upper contacts of sequence switch cams 110 and 111 to the right-hand windings of the repeating coils RC, and through the 50 winding of the calling supervisory relay 130. Sequence switch 100 also opens the holding circuit of relay 314 of the sender at sequence switch cam 103, whereupon relay 314 deenergizes, closing a circuit extending from 55 ground at its left-hand armature and back contact over the left-hand contact of sequence switch cam 303 (2 to 16), and through the winding of sequence switch magnet 300 for driving sequence switch 300 60 out of position 16 and into normal position 1. The circuits of the sender are now restored to normal.

Following the units selection movement 65 of the final selector switch 201, the terminals of the called line B are tested in the well-

known manner, and if the line is found idle, a talking connection is cut-through from the calling subscriber's line over the contacts of jack J and plug P through the windings of repeating coil RC, over the wipers of office 70 selector switch 116, wipers of the incoming selector switch 200 and the wipers of the final selector switch 201. Following the application of ringing current to the line of the called subscriber and the response of the 75 called subscriber, supervisory relay 130 functions in the usual manner to give the operator a signal.

Upon the termination of the conversation, 80 the subscribers restore their receivers to the switch-hooks, thereby causing the operation of the answering supervisory relay 131, and the calling supervisory relay 130 to indicate to the operator that the conversation is finished and that she may take down the connection. In response to these signals, the operator withdraws the plug P from jack "J", causing thereby the deenergization of cut-off relay 10 and of relay 112. The de-energization of cut-off relay 10 restores the 85 connection of the subscriber's line relay 18 to the subscriber's line.

The deenergization of relay 112 establishes a circuit extending from grounded battery through the winding of sequence switch 90 magnet 100 through the upper right-hand contact of sequence switch cam 102 (2 to 16) and thence to ground at the back contact and armature of relay 112. Sequence switch 100 thereupon moves into position 18 in 100 which position a circuit is established for the down-drive magnet 132 for restoring the switch shaft of the office selector 116. This circuit may be traced from grounded battery through the winding of the down-drive magnet 132 and thence to ground through the upper right-hand contact of sequence switch cam 105 (18). Down-drive magnet 132 upon energizing presses the depending portion 120 of the switch shaft against the constantly rotating down-drive roller 133, thereby causing the restoration of the switch shaft to normal. When the switch shaft reaches normal, a circuit is established extending from ground at brush 129 over normal commutator segment 134 through the upper right-hand contact of sequence switch cam 106, and thence through the magnet winding of sequence switch 100 to grounded 110 battery for driving sequence switch 100 into normal position.

The restoration of the incoming and final selector switches then proceeds in the well-known manner.

Connection with an office equipped with 125 step-by-step switches.

If it be assumed that the calling subscriber desires a connection with subscriber C, whose line terminates in the office 130

which is equipped with step-by-step switches, and that the designation of subscriber's line C is 36975, the circuits function in the manner previously described up to the 5 point where sequence switch 300 of the office sender is driven into position 4 and the fundamental circuit is established between the stepping relay 316 and relay 115 of the office selector switch, with the exception that 10 the operator has depressed the #3 office key for directing the movement of the office selector to a group of trunks leading to the office Y.

The energization of stepping relay 316 15 over the fundamental circuit including the winding of relay 115, establishes a circuit extending from ground at the armature of relay 316 through the upper left-hand contact of sequence switch cam 307 (4) through 20 the lower left-hand contact of office register cam 417 (3), over conductor 354, armature and back contact of counting relay 3', the winding of counting relay 3, and thence to grounded battery. Counting relay 3 there- 25 upon energizes closing a locking circuit for itself extending through the winding of relay 3'. Relay 3', however, does not energize at this time since its winding is shunted by ground on conductor 354. As soon, how- 30 ever, as the brush 123 engages the first con- ducting segment of commutator 124, relay 316 deenergizes in the manner previously described, thereby removing ground from conductor 354. Relay 3' thereupon ener- 35 gizes, transferring ground on conductor 354 through its armature and front contact, and armature and back contact of relay 2' to the winding of relay 2.

The counting relays 2' to 0' energize in 40 succession in the manner previously de- scribed during the group selection move- ment of the office selector switch. When relay 0' energizes, the fundamental circuit is opened and a circuit is closed through its 45 left-hand armature and front contact for driving sequence switch 300 out of position 4 and into position 6, this circuit extending from grounded battery through the winding of sequence switch 300 through sequence 50 switch cam 312 (4), the front contact and left-hand armature of relay 0', and thence to ground at the upper left-hand contact of sequence switch cam 308 (4). When se- 55 quence switch 300 leaves position 4, the locked-up counting relays become deener- gized. In position 6, since the office register has now been set to position 3 for selection of office Y, a circuit is now established for driving sequence switch 300 through position 60 6 and into position 8. This circuit may be traced from grounded battery through the winding of sequence switch 300 through se- 65 quence switch cam 313 (6), and thence to ground at the upper right-hand contact of office register cam 415 (3). The purpose

of driving the sender sequence switch through position 6 is to eliminate one selec- tive position which is necessary for transla- tion when a connection is established with an office having switches of the power-driven 70 panel type.

Upon the opening of the fundamental circuit when counting relay 0' energizes, following office selection, the sequence switch of the office selector was driven into position 75 6 and an idle trunk in the selected group was selected in the manner previously described. Upon the selection of such idle trunk, the sequence switch 100 was driven into position 80 11, in which position conductors 117 and 118 of the fundamental circuit were connected over the talking wipers 134 and 135 of the office selector to the trunk terminating in the first selector switch 250 of office Y.

A new fundamental circuit is now estab- 85 lished extending from grounded battery through the right-hand winding of line relay 251 of selector switch 250, through the side switch wiper 252 and its first position contact, over trunk conductor 253, wiper 134 of the office selector, sequence switch cam 110 (11), conductor 117, the right-hand armature and back contact of stepping relay 315, sequence switch contact 311' (6 to 18), register cam 418 (3), sequence switch cam 312' (6 to 18), 90 winding of stepping relay 316, the upper right-hand contact of sequence switch cam 306, (5 $\frac{3}{4}$ to 14), conductor 319, the lower left-hand contact of office register cam 414 (3), conductor 318, conductor 118, sequence 95 switch cam 111 (11), wiper 135 of the office selector, trunk conductor 254, side-switch wiper 255 and its first position contact, and thence through the left-hand winding of line relay 251 to ground. Line relay 251 100 and stepping relay 316 energize in this cir- cuit, relay 251 preparing the stepping cir- cuit of the first selector switch 250 for stepping the wiper shaft in its vertical se- 105 lective movement.

Stepping relay 316 upon energizing closes a circuit extending from ground at its ar- mature contacts, through the contact of se- 110 quence switch cam 309 (8), the upper con- tact of office register cam 416 (3), the upper left-hand contact of thousands register cam 423 (6), conductor 356, the armature and back contact of counting relay 6', and thence through the winding of counting relay 6 to 115 grounded battery. Counting relay 6 ener- gizes in this circuit and establishes a locking circuit for itself through the winding of relay 6'. Relay 6', however, does not ener- 120 gize in this circuit since its winding is shunted by ground on conductor 356.

Since the office register has been posi- 125 tioned in position 3 for the selection of an office having step-by-step switches, a circuit is established for stepping relay 315 which may be traced from grounded battery 130

through interrupter 487, office register cam 419 (3), winding of stepping relay 315, sequence switch cam 313', closed in positions 8 to 18 inclusive, the left-hand armature and back contact of counting relay 0' and thence to ground at the upper left-hand contact of sequence switch cam 308 (8). Through the operation of interrupter 487, relay 315 causes the opening and closing of the fundamental circuit and the consequent deenergization and energization of stepping relay 251 of the first selector switch and of sender stepping relay 316. Relay 315 upon each energization closes a holding circuit extending through its armature and front contact to ground at the lower contacts of sequence switch cam 308 independent of the contacts of relay 0' to insure a full length of circuit opening for the last impulse of each set of impulses as relay 0' might otherwise open the circuit of relay 315 before the interrupter 487 had held relay 315 energized the necessary period.

The successive deenergizations of relay 251 causes the vertical stepping movement of the first selector switch in the well-known manner. The first deenergization of relay 316 removes the shunt from around the winding of counting relay 6' which thereupon energizes, transferring through its armature and front contact the ground on conductor 356 to the winding of relay 5. Upon successive deenergizations of stepping relay 316 through the operation of stepping relay 315, counting relays 5' to 0' become energized. Upon the energization of counting relay 0', following the seventh step of the first selector 250, the circuit extending through the winding of stepping relay 315 is opened at the left-hand armature and back contact of relay 0' to arrest the intermittent opening and closing of the fundamental circuit. The attraction of the right-hand armature of relay 0' is at this time without function since the right-hand contacts of this relay are now shunted through sequence switch contacts 311' and 312' and cam 418 of the office register for the purpose of maintaining the fundamental circuit closed between series of impulses.

Upon the energization of relay 0' a circuit is also closed extending from grounded battery through the winding of the slow-to-energize relay 320, which circuit may be traced from grounded battery through the winding of this relay over conductor 321, the lower left-hand contact of office register cam 413 (3), conductor 322, front contact and left-hand armature of relay 0', and thence to ground through the upper left-hand contact of sequence switch cam 308 (8). Relay 320 energizes in this circuit and after an interval closes its contacts thereby establishing a circuit for driving sequence switch 300 out of position 8 into position

10. Relay 320 is so designed that it will not close its contacts until sufficient time has elapsed for the selector 250 to function in its trunk hunting movement following the positioning of its shaft wipers opposite a level 70 of contacts in its bank leading to the selected thousands section of the office.

As soon as sequence switch 300 leaves position 8, the locking circuit of the counting relays is opened and the locked-up relays 75 thereupon deenergize. Upon reaching position 10, since at this time stepping relay 316 is energized over the fundamental circuit extending through side-switch wipers 252 and 255 in contact with their third position 80 contacts and the wipers of selector 250 to the line relay (not shown) of the second selector 256, a circuit is established from ground through the armature contacts of stepping relay 316 through the upper right-hand contact of sequence switch cam 307 (10), the upper right-hand contact of the hundreds register cam 433 (9), conductor 353, the armature and back contact of counting relay 9', and thence through the 90 winding of relay 9 to grounded battery. Relay 9 energizes in this circuit and closes a locking circuit for itself, extending through the winding of relay 9', but relay 9' does not energize in this circuit since its 95 winding is shunted by ground on conductor 353. Upon the first opening of the fundamental circuit through the energization of stepping relay 315 in the manner previously described, relay 316 deenergizes in unison 100 with the stepping relay of the second selector switch, thereby removing ground from conductor 353 and permitting counting relay 9' to energize.

Upon successive openings of the fundamental circuit through the operation of stepping relay 315, counting relays 8' to 0' energize in succession and lock up over cam 308 (10 to 101). Following the last opening of the fundamental circuit, counting relay 0' energizes, opening the circuit of stepping relay 315 and closes the circuit previously traced for relay 320, which after an interval closes a circuit for driving sequence switch 300 out of position 10 and into position 12. The 110 successive openings of the fundamental circuit have caused the stepping of the second selector switch to the tenth level from which access may be had to lines of the nine hundreds group, and the second selector 115 switch thereupon starts in its rotary movement for selecting an idle trunk of the selected group.

When sequence switch 300 moves out of position 10, the locked-up counting relays become deenergized and the circuit of stepping relay 315 is again established through the back contact and left-hand armature of counting relay 0'. As soon as the second selector switch 256 connects with an idle trunk 130

of the tenth level, extending to an idle final connector 257, the fundamental circuit is again established through the line relay (not shown) of the final connector switch 257 and 5 through the stepping relay 316 of the sender.

Relay 316 now energizes closing a circuit extending from ground at its armature contacts, through the lower right-hand contact of sequence switch cam 307 (12), the lower 10 left-hand contact of the tens register cam 441 (7), conductor 357, the armature and back contact of counting relay 7', and thence through the winding of counting relay 7 to grounded battery. Counting relay 7 energizes in this circuit and closes a locking circuit for itself extending through the winding of relay 7'. Relay 7', however, does not energize at this time since its winding is 15 shunted by ground on conductor 357. Upon 20 the first opening of the fundamental circuit by stepping relay 315, the stepping relay of the final connector switch and the stepping relay 316 of the sender deenergize, stepping relay 316 removing ground from conductor 25 357, thereby permitting the energization of counting relay 7'.

Stepping relay 315 causes successive openings of the fundamental circuit to cause the vertical stepping of the final selector switch 30 and successive deenergizations of stepping relay 316 of the sender. Counting relays 6' to 0' thereupon energize in succession and remain locked up over sequence switch cam 308 (12 to 121). Upon the energization of 35 counting relay 0', the circuit of stepping relay 315 is opened at the left-hand armature and back contact of relay 0' to discontinue the intermittent opening of the fundamental circuit, and a circuit previously 40 traced is closed for energizing relay 320, which in turn after an interval closes a circuit for driving sequence switch 300 out of position 12 and into position 14.

Sequence switch 300 upon leaving position 45 12 opens the locking circuit of the locked-up counting relays, which thereupon deenergize, counting relay 0' re-establishing the energizing circuit of stepping relay 315. Immediately following the vertical stepping 50 movement of the connector switch, the fundamental circuit through stepping relay 316 is again established, and with sequence switch 300 in position 14, a circuit is established from ground at the armature contacts of 55 relay 316 through the lower left-hand contact of sequence switch cam 307 (14), the upper right-hand contact of the units register cam 451 (5), conductor 358, the armature and back contact of counting relay 5', and thence from the winding of counting 60 relay 5' to grounded battery. Relay 5 energizes in this circuit and closes a locking circuit for itself extending through the winding of relay 5'. Relay 5', however, does not 65 energize at this time since its winding is

shunted by ground on conductor 358. Upon the first opening of the fundamental circuit by stepping relay 315, the stepping relay of the connector and stepping relay 316 of the sender deenergize. Relay 316 removes 70 ground from conductor 358 permitting the energization of counting relay 5' which thereupon transfers ground from conductor 358 through its armature and front contact, the armature and back contact of relay 4' to the winding of counting relay 4.

Stepping relay 315 causes successive openings of the fundamental circuits to cause the rotary stepping movement of connector switch 257 and successive deenergizations of stepping relay 316, which in the manner previously described causes the successive energization of counting relays 5' to 0'.

Upon the energization of relay 0', the circuit for stepping relay 315 is opened at the left-hand armature and back contact of relay 0', and a circuit is established for relay 320 for driving sequence switch 300 out of position 14 and into position 16. Sequence switch 300 upon leaving position 14 opens the locking circuit of the locked up counting relays. Upon moving into position 16 a circuit is closed over sequence switch cam 311 for driving sequence switch 100 of the office selector out of position 11 and into position 16. Upon leaving position 11 relay 314 is deenergized causing the movement of the sender sequence switch 300 out of position 16 and into normal position.

Upon the movement of sequence switch 100 of the office selector into position 16, the talking circuit is cut through from the calling subscriber's line to the connector 105 switch 257, and the testing of the terminals of the called line C and ringing up the called subscriber proceed in the well-known manner. The restoration of the connection following the termination of the conversation takes place in substantially the same manner as described in connection with the explanation of a connection to office X.

From the preceding description it will 110 be apparent to those skilled in the art that a sender fundamentally designed for use in controlling the setting of switches of the power-driven type has been employed in a very simple manner for controlling either switches of the power-driven type or switches of the step-by-step type, the alteration of the circuits of the sender for controlling switches of either type being dependent entirely upon the setting of the office register which controls the setting of the office selector switch to determine the particular office to which the connection is to be extended.

While the invention has been disclosed 115 in connection with a system of the semi-

automatic type in which the operator sets up the designation of the desired line upon her bank of keys, it is to be understood that the invention might equally well be applied to a system of the full automatic type in which the registers are set directly by the calling subscriber through the manipulation of the sending dial associated with the sub-station apparatus. Such a full automatic system is disclosed in the patent to Polinkowsky, No. 1,193,053, issued August 1, 1916.

What is claimed is:

1. In a telephone exchange system, a plurality of offices, a plurality of switches arranged to be driven from a continuously operating source of kinetic energy, in certain of said offices, a plurality of step-by-step switches in other of said offices, and a switch controlling mechanism associated with each of said certain offices comprising means for registering line designations, means under the control of said registering means for selectively controlling the operation of said first mentioned switches to extend connections within the office with which it is associated or to other offices, and means for altering the circuits of said mechanism whereby said step-by-step switches are controlled by said mechanism when connections have been extended to offices having step-by-step switches.
2. In a telephone exchange system, an originating office, a plurality of distance offices, a switch in said first office arranged to be driven from a continuously operating source of kinetic energy for extending connections to any one of said distant offices, a plurality of switches in certain of said distant offices, arranged to be driven from a continuously operating source of kinetic energy, a plurality of step-by-step switches in other of said distant offices, and a switch controlling mechanism in said originating office comprising means for registering line designations, means under the control of said registering means for selectively controlling the operation of said switch in said originating office to extend a connection to any one of said distant offices and for controlling the switches of the distant office if the connection is extended to an office having switches arranged to be driven from a continuously operating source of kinetic energy and means for altering the circuits of said mechanism whereby said step-by-step switches are controlled by said mechanism when the connection is extended to an office having step-by-step switches.
3. In a telephone exchange system, an originating office, a plurality of distant offices, a switch in said first office arranged to be driven from a continuously operating source of kinetic energy for extending connections to any one of said distant offices, a plurality of switches in certain of said offices arranged to be driven from a continuously operating source of kinetic energy, a plurality of step-by-step switches in other of said offices, a set of registers associated with each of said first mentioned offices, means for variably positioning said registers, means under the control of said registers for selectively controlling the operation of said first mentioned switches to extend connections within the office with which said registers are associated or to other offices and means for altering the circuits of said second means whereby said step-by-step switches are controlled by said second means when connections have been extended to offices having step-by-step switches.
4. In a telephone exchange system, a plurality of offices, a plurality of switches in certain of said offices arranged to be driven from a continuously operating source of kinetic energy, a plurality of step-by-step switches in other of said offices, a set of registers associated with each of said first mentioned offices, means for variably positioning said registers, means under the control of said registers for selectively controlling the operation of said first mentioned switches to extend connections within the office with which said registers are associated or to other offices and means for altering the circuits of said second means whereby said step-by-step switches are controlled by said second means when connections have been extended to offices having step-by-step switches.
5. In a telephone exchange system, a plurality of offices, a plurality of switches in certain of said offices arranged to be driven from a continuously operating source of kinetic energy, a plurality of step-by-step switches in other of said offices, a set of registers associated with one of said first mentioned offices, means for variably positioning said registers, means under the control of said registers for selectively controlling the operation of said first mentioned switches to extend connections within the office with which said registers are associated or to other offices and means for altering the circuits of said second means whereby said step-by-step switches are controlled by said second means when connections have been extended to said offices having step-by-step switches.
6. In a telephone exchange system, a plurality of offices, a plurality of switches in certain of said offices arranged to be driven from a continuously operating source of kinetic energy, a plurality of step-by-step switches in other of said offices, a set of reg-
